FIG. 1

FIG. 2

FIG. 3

FIG. 4

FIG. 1 is an elevational view of a preferred embodiment of my invention of a bilboquet ball, with a portion of a typical tether extending therefrom;

FIG. 2 is a bottom view of the ball shown in FIG. 1, illustrating a socket having a beveled mouth opening through the bottom of the ball;

FIG. 3 is an elevational view, similar to FIG. 1, but illustrating another embodiment in the form of a wider bilboquet ball; and

FIG. 4 is an elevational view, similar to FIGS. 1 and 3, but illustrating still another embodiment in the form of a narrower bilboquet ball.

I claim:

The ornamental design for a bilboquet-type ball or the like, as shown and described.
